UNITED STATES PATENT OFFICE.

GEORGE HENRY DUNLOP, OF AUBURN, VICTORIA, AUSTRALIA.

EXCAVATING-MACHINE.

1,236,691.

Specification of Letters Patent. Patented Aug. 14, 1917.

Application filed June 26, 1911. Serial No. 635,332.

To all whom it may concern:

Be it known that I, GEORGE HENRY DUNLOP, a subject of the King of Great Britain and Ireland, residing at No. 20 Robinson's road, Auburn, Victoria, Australia, have invented new and useful Improvements in Excavating-Machines, of which the following is a specification.

This invention relates to machinery of 10 the type in which a scoop or bucket is dragged along the ground by a filling rope until it is filled with earth or other material; is hoisted by a hoist-conveying rope passing from the scoop over the pulley on 15 the jib of the derrick or crane; is conveyed by swinging the said jib; and is dumped by being overturned over the place where the load of earth or other material is to be deposited.

20 The improvements constituting this invention consist in the use of two hoist-conveying ropes, and in the method and means by which they, and parts which may be employed in conjunction with them, are 25 used as for example in operating a scoop.

My invention will now be described aided by a reference to the attached sheets of drawings in which:

Figure 1 is a plan, and

30 Fig. 2 a side elevation showing the excavating machine with the scoop in position for filling, being hoisted full, and being dumped. The latter two positions are indicated in dotted lines.

35 Fig. 3 is a view similar to Fig. 2 but showing a tipping rope passing direct to a winding drum at the lower part of jib.

Fig. 4 is a side elevation showing the scoop, filling rope, hoist-conveying ropes 40 and a multiple tackle connected with the filling rope.

Fig. 5 is a part side view, and

Fig. 6 a part plan of an adjusting socket and a brake at the foot of the jib.

45 The machine consists of a derrick or crane 1, having a swinging jib 2, and excavating scoop or bucket 3, a filling rope 4 passing from a winding drum 5 on the derrick to the scoop 3, and connected to the latter near 50 the mouth or cutting edge thereof by the usual spreading chains, or by a rigid bail 6 as may be found preferable; two hoist-conveying ropes 7^a and 7^b passing from two winding drums 8^a and 8^b on the derrick 1 55 over two pulleys 10 at the outer end of the

jib 2 to the scoop 3 to which they are connected.

The filling rope 4 passes from the winding drum 5 conveniently placed on the derrick over a guide pulley 13, thence downward 60 and partly around a guide pulley 14 at the foot of the jib and on to the scoop, the two guide pulleys being so arranged that the rope passing between them is, for a short distance, vertical and centrical over the pivot 65 at the foot of the jib 2. The winding drums 8^a and 8^b for the hoist-conveying ropes are placed sufficiently apart one at each side of the fore and aft center line of the derrick; the jib swings around a pivot on this center 70 line at one end of the derrick; at each side of the pivot approximately at right angles to the center line and about as far apart as the winding drums there are single pulleys arranged in a well known way, or pairs of 75 them 16, fixed to parts of the frame of the machine that do not swing with the jib, to suitably guide the hoist-conveying ropes 7^a and 7^b as the jib is swung. The filling 80 drum 5 may be mounted at the middle, and 80 the hoist-conveying drums 8^a and 8^b, one at each end of the shaft 9 on the derrick placed at right angles to the fore and aft center line, and each drum should be fitted with a 85 brake and a clutch—preferably of the friction type and furnished with the usual operating levers.

A brake 11 is shown fitted at the foot of the jib 2 (Figs. 5 and 6) which will have a lever or treadle suitable for operation by an 90 attendant in order to hold the jib if necessary, over any particular place, as for example over the cutting where the scoop is being filled, or over the embankment where the scoop may be delayed owing to sticky 95 material adhering to the scoop and so forth.

In hard ground it may be found that the power available on the filling rope is insufficient. Now, as shown and as is well known, in derrick cranes having fixed frame works 100 combined with swinging jibs, it is usual practice to have the line passing from the jib to the fixed portion of the machine, with some part of its length vertical and centrical over or under the pivot. In ordinary constructions there would not be space for multiplying tackle such as a rope and pulleys under the pivot, but such multiplying tackle 105 12 can be conveniently arranged above the pivot as shown in Fig. 4, in order to give 110

greater power for filling the scoop when required in hard ground.

For jibs having very long booms, such as may be used with the excavator described, it is desirable to give as rigid a fixing as possible at the foot of the jib. For this purpose the boom is shown fitted into an adjusting socket 20 at the foot, and secured thereto by bolts. In order that the outer end of the boom may be raised or lowered within limits, the socket may be splayed outwardly and the boom made circular at the end, as from a center at the principal through holding bolt 21, while further holding bolts 22 pass through slotted holes 23 in the socket. By this construction the outer end of the boom can be set at any desired elevation, within limits, and the foot then rigidly clamped to the casting by means of the bolts 21 and 22, and plate washers may be used under the nuts, covering the outer ends of the two pieces used to form the boom as shown. The spaces between the splayed parts of the casting and the boom may be filled by timber wedges 24 or the like.

Let it be assumed that the improved excavating machine, according to this invention, is being used to excavate a channel and to deposit the earth in one or two side embankments.

First let it be understood that the excavated material is all to be placed in one side embankment on the right-hand side of the cutting when looking from the derrick toward the outer end of the jib. Then the left hand-hoist-conveying rope passes over a pulley at the outer end of the jib, as explained, and is attached to the back of the scoop; while the right-hand hoist-conveying rope passes over a pulley at the outer end of the jib, but somewhat nearer the pivot than the other, and is attached by bars or chains to the scoop in such a way as may be most convenient so that the filled scoop when hoisted will carry its load without spilling, but preferably by spreading chains as for example, one to each front top corner and one to the back of the scoop. Now assume that the scoop is filled in the cutting, for example, to the leftward of the fore and aft center line of the derrick. Then the cycle of operations per scoopful of earth will be as follows:—Hoist by the right-hand hoist-conveying rope 7^a, keeping the brakes applied to the drums for the left-hand hoist-conveying rope 7^b, and the filling rope 4 so that there shall be no unnecessary slack. As the right-hand hoist-conveying rope 7^a passes from the jib-head pulley around the guide pulley some distance aside from the pivot at the foot of the jib, it is evident that this rope when the scoop is suspended by it will apply a pull at the jib-head tending to swing the jib to the right. When the scoop is hoisted high enough and conveyed over the

embankment site, the driver applies the brake (or it may be the friction clutch) to hold the drum of the left-hand hoist-conveying rope 7^b, and at the same time throws out the clutch and slacks out the right hand hoist-conveying rope 7^a. This causes the scoop to drop until it is suspended by the hoist-conveying rope 7^b attached to the back of the scoop so that the open mouth is downward to dump the load of earth; and now the weight of the scoop, as it is being lowered out by the left-hand hoist-conveying rope 7^b controlled by the brake, causes the jib to swing leftward in a similar manner to that above described for the rightward swing. The scoop is lowered down in this way until the cutting edge rests on the ground where the scoop is to be filled, and then the filling rope 4 is applied to haul the scoop forward to fill it, while the back of the scoop may be held tilted up by the left-hand hoist-conveying rope 7^b sufficiently to cause the scoop to cut into the earth, especially in the earlier stage of the filling operation. It is evident that with the appliances and in the manner described the scoop may be dumped either gently, so as not to damage wagons, or with a jerk so as to throw out sticky material.

Second let it be assumed that the scoop is to be dumped sometimes over the right-ward embankment, and sometimes over the left-ward embankment, and it may be alternately. Then the right-hand and the left-hand hoist-conveying ropes 7^a and 7^b respectively pass from their respective winding drums over jib-head pulleys side by side on the same pin at the position indicated in Fig. 3, and down to the shackle at the top of a rigid bridle 25, in which the scoop is so mounted pivotally that the filled scoop may be hoisted carrying its load of earth, and rotated by means of the tipping rope 26 operated by the drum 27 according to Australian Patent No. 12,102 so as to dump the contents. So attached the left-hand hoist conveying rope may be employed to hoist the filled scoop and convey it over the left-ward embankment, and the right hand hoist-conveying rope to lower the empty scoop and convey it to the place where it is again to be filled, and vice versa.

The guide pulleys for the hoist-conveying ropes at each side of the pivot upon which the jib swings are placed far enough apart each way from the pivot to give sufficient lateral pull either way to swing the jib, as for example by the suspended weight of the empty scoop. But the ropes may be so arranged that more than half of the weight of the scoop may be on one hoist-conveying rope, and the remainder on the other, so as to reduce the swinging speed, using the apparatus herein described.

It is evident that if, as shown in Fig. 1, the inner of each pair of guide pulleys used for swinging the jib be set forward, and the

outer one backward, from the line through the pivot of the jib at right angles to the center line of the machine, a greater leverage can be obtained for swinging the jib at 5 its sideward positions than if the pulleys were set with their centers on that line.

Any well known type of derrick may be used having part of the frame upon which the swinging guide pulleys for the hoist- 10 conveying ropes may be suitably fixed at each side of the jib pivot, so that they do not swing with the jib.

One hoist-conveying rope is used to hoist the scoop and swing the jib one way, the 15 other hoist-conveying rope to lower and swing the opposite way. When the filled scoop is always swung one way the rope used to hoist it is attached suitably for raising the scoop without spilling the contents.

20 The other rope is attached suitably for overturning the scoop to dump the contents and to lower it onto the ground on the cutting edge suitably for refilling. When the loaded scoop must be swung either way the two 25 ropes are arranged similarly so that either may be used to raise or lower the scoop, and in this case either the machine will be fitted with a tipping rope and gear according to Australian Patent No. 12,102, or a dump 30 hook under the head of the jib and a catch or bail on the scoop to engage therewith will be used to dump the scoop. Either with the tipping rope or dump-hook but more especially with the latter, the scoop should be 35 so designed as to hang mouth downward when empty, so that it will drop onto the cutting edge when lowered onto the ground to fill. To hoist without swinging the jib or to hold the jib without swinging when 40 the scoop is suspended, both hoist-conveying ropes must be used each loaded equally or nearly so. But if necessary the jib may be fitted with a brake operable by the driver to control the swinging.

45 A crane of the ordinary locomotive type might be used with suitable guide pulleys for the hoist-conveying ropes but I prefer a derrick in which all parts of the machine are stationary while excavating, except the 50 jib which is rotatably set on a pivot at one end of the machine in a well known way.

For operating the scoop I prefer three drums each with friction clutch and brake mounted on one cross shaft and this construction is especially suitable where the motor is continuously running, as for example with an internal combustion engine.

55 The derrick may be suitably mounted and geared for movement along as the work progresses.

Having now described my invention what I claim as new and desire to secure by Letters Patent is:—

1. In an excavating machine, in combination, a support provided with a jib, a scoop, 65 a filling line applied to the scoop, a guide pulley adjacent to the foot of the jib and to which said line extends, a winding drum for actuating said line, and multiple tackle comprising a rope and pulleys arranged vertically above the foot of said jib and operatively interposed between said drum and said line.

2. In an excavating machine, in combination, a derrick comprising a laterally swingable jib and a relatively fixed support extending upwardly above the foot of the jib, 75 a scoop, a hoist-conveying cable attached to said scoop, the jib provided with a pulley arranged approximately at its point and receiving said cable, said support having a guide pulley for said cable arranged to one side of the axis on which said jib swings, a winding drum for actuating said cable, 80 guide pulleys arranged approximately at the foot of the jib and a distance above said foot and approximately in the vertical line of the axis on which said jib swings, a filling connection for said scoop and extending therefrom and over said last mentioned pulleys whereby said connection embodies a 85 portion arranged vertically over the foot of the jib, and a winding drum for actuating said filling connection.

3. In an excavating machine, in combination, a derrick comprising a laterally swingable jib and a relatively fixed support extending vertically above the foot of the jib, 90 an axis mounted upon said derrick and to the rear of the foot of said jib, said axis carrying a series of winding drums, hoisting cables passing from the two outermost of said drums over pulleys at the point of said jib and depending downwardly therefrom, a scoop carried by said depending 95 cables, said vertical support carrying multiple tackle comprising a rope and pulley arranged vertically above the foot of said jib, a filling cable fastened at one end to the open end of said scoop and passing 100 through and over said multiple tackle to a winding drum located centrally upon said afore-mentioned drum carrying shaft.

In testimony whereof I have signed my name to this specification in the presence of 115 two subscribing witnesses.

GEORGE HENRY DUNLOP.
